UNITED STATES PATENT OFFICE

ALFRED G. KINTZ, OF WALLINGFORD, CONNECTICUT, ASSIGNOR TO INTERNATIONAL SILVER COMPANY, OF MERIDEN, CONNECTICUT, A CORPORATION OF NEW JERSEY

DESIGN FOR A DISH OR OTHER ARTICLE OF HOLLOW WARE

Application filed January 24, 1930. Serial No. 34,263. Term of patent 14 years.

To all whom it may concern:

Be it known that I, ALFRED G. KINTZ, a citizen of the United States, residing at Wallingford, county of New Haven, and State of Connecticut, have invented a new, original, and ornamental Design to be applied to a Dish or Other Article of Hollow Ware, of which the following is a specification, reference being had to the accompanying drawing, forming a part thereof.

Fig. 1 is a fragmentary view illustrative of

my invention, and Fig. 2 is a top plan view of a dish embodying my new design the edge of the dish being of conventional thickness and the bowl of the dish of conventional depth.

I claim:

The ornamental design for a dish or other article of hollow ware as shown and described.

ALFRED G. KINTZ.
